(57) **CLAIM**

The ornamental design for a connecting bracket for handrails, as shown and described.

DESCRIPTION

FIG. 1 is a front view of a connecting bracket for handrails, showing my new design;

FIG. 2 is a top plan view thereof;

FIG. 3 is a bottom plan view thereof;

FIG. 4 is a rear plan view thereof;

FIG. 5 is a left plan view thereof;

FIG. 6 is a right plan view thereof; and,

FIG. 7 is a perspective view thereof.

The broken lines represent portions of the connecting bracket for handrails that form no part of the claimed design.
